US0D1071358S

(12) **United States Design Patent** (10) Patent No.: **US D1,071,358 S**
(45) Date of Patent: ** Apr. 15, 2025

(54) **PROTECTIVE HELMET**

(71) Applicant: **MSA Technology, LLC**, Cranberry Township, PA (US)

(72) Inventors: **James Andrew Chilson**, Zhejiang (CN); **Remi Pascal Finiel**, Zhejiang (CN)

(**) Term: **15 Years**

(21) Appl. No.: **35/519,727**

(22) Filed: **Oct. 19, 2023**

(80) **Hague Agreement Data**

Int. Filing Date: **Oct. 19, 2023**

Int. Reg. No.: **DM/234412**

Int. Reg. Date: **Oct. 19, 2023**

Int. Reg. Pub. Date: **Jan. 19, 2024**

CLAIM

The ornamental design for a protective helmet as shown and described.

DESCRIPTION

1. Protective helmet

1.1 : Bottom

1.2 : Front

1.3 : Perspective

1.4 : Left

1.5 : Back

1.6 : Right

1.7 : Top

Safety helmet shell with "V" shaped geometry features and external hardware for securing accessories. The equal-length broken lines in the reproductions depict portions of the protective helmet that form no part of the claimed design.

1 Claim, 7 Drawing Sheets
